[57] CLAIM

The ornamental design for a baseball cap jewelry pendant, as shown and described.

DESCRIPTION

FIG. 1 is a front perspective view of the preferred embodiment of the baseball cap jewelry pendant of the instant invention, showing the new design;

FIG. 2 is a top planar view thereof;

FIG. 3 is a bottom planar view thereof;

FIG. 4 is a left side elevational view thereof;

FIG. 5 is a right side elevational view thereof;

FIG. 6 is a front side elevational view thereof;

FIG. 7 is a rear side elevational view thereof; and,

FIG. 8 is a front elevational view shown in a position of use, the broken line showing of a figure and attachment chain is for illustrative purposes only and forms no part of the claimed design.
